(57) **CLAIM**

The original design for a beam clamp, as shown and described.

DESCRIPTION

FIG. 1 is a front right perspective view of a beam clamp showing our new design;

FIG. 2 is a rear right perspective view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a rear elevational view thereof;

FIG. 8 is a rear right perspective view thereof, shown joined with a second beam clamp;

FIG. 9 is a front right perspective view thereof, shown joined with a second beam clamp in an alternate position of use;

FIG. 10 is a front left perspective view thereof, shown in a further alternate position of use;

FIG. 11 is a right side elevational view thereof, shown in a further alternate position of use; and,

FIG. 12 is another right side elevational view thereof, shown the position of use of FIG. 9.

The broken line showing of a second beam clamp in some of the figures is for illustrative purposes only and forms no part of the claimed design.
